UNITED STATES PATENT OFFICE.

HOWARD E. HARBAUGH, OF ROCKFORD, ILLINOIS, ASSIGNOR TO THE S. B. WILKINS COMPANY, OF SAME PLACE.

CIRCULAR-KNITTING MACHINE.

SPECIFICATION forming part of Letters Patent No. 372,535, dated November 1, 1887.

Application filed October 20, 1885. Serial No. 181,272. (No model.)

To all whom it may concern:

Be it known that I, HOWARD E. HARBAUGH, a citizen of the United States, residing in the city of Rockford, in the county of Winnebago and State of Illinois, have invented new and useful Improvements in Circular-Knitting Machines, of which the following is a specification.

This invention relates to knitting-machines in which the needles move endwise in grooves formed in the needle-supporting cylinder of the machine, and in which the endwise movement of the needles in their grooves is produced by the operating-cams moving against the needles or the needles moving against the cams.

The object of this invention is to prevent breakage of needles or other injury to the machine resulting from the needles striking against the ends of the moving cams or the ends of the moving cams striking against the needles; and it consists in supplementary yielding cams pivoted in suitable positions to engage the needles and prevent them colliding with the points of the fixed cams.

To this end I have designed and constructed the improvements represented in the accompanying drawings, in which—

Figure 1 is a perspective representation of a portion of the rotary cam-cylinder of a rotary knitting-machine to which I have applied my improvements. Figs. 2 and 3 are outstretched inner face perspective representations of a portion of the cam-cylinder with my improvements in place thereon. Fig. 4 is an outside section in perspective on dotted line 1 on Fig. 2. Fig. 5 is a representation of a needle. Figs. 6 and 7 are outstretched inner face representations in perspective of a portion of the cam-cylinder, showing modifications of my improvements in place thereon. Fig. 8 is an outside section of the cam-cylinder in perspective on dotted line 2 on Fig. 6; and Fig. 9 is an outside section of the cam-cylinder in perspective on dotted line 3 on Fig. 7.

The cam-cylinder represented in the figures is of the form employed in what is known as the Franz & Pope knitting-machine, (see United States Letters Patent Nos. 99,425 and 99,426,) and so far as concerns the cylinder A,

the fixed cams B and C, the adjustable stitch-cam D, the adjustable cams E and F, and the lower fixed cam, H, they are in every particular substantially identical with like parts of said machine as now manufactured.

In knitting-machines employing cams substantially such as shown, having dividing or switch ends, it is found that the right-angled arms *a* of the needles *b* which engage the cams are at times thrown in position to engage the switch ends thereof, and under the required movement of the cam-cylinder on the needle-supporting cylinder, or of the needle supporting cylinder within the cam-cylinder, the needles are broken, and in most instances the machine is otherwise injured, to prevent which I have employed the pivoted supplemental switch-cams *c* and *d* in connection with the fixed cams B and C and the pivoted latch *e* in connection with the stitch-cam D and the adjustable cam E.

The pivoted supplementary switch cams are in the main, in outline, of obtuse-angled triangular form, having a pivotal connection of their obtuse angular bevel-points with the cam-cylinder in such relative position with the fixed cams that the upper edges of their inner ends shall engage the under faces of the fixed cams and their free outer ends extend in substantially the same annular lines in the cylinder with the free ends of the fixed cams.

The upper edges of the switch-cams are notched to receive the free ends of the fixed cams to permit the switch-cams to turn on their pivotal supports and their free ends to rise from their dotted-line position to their solid-line position, as shown at *d* in Fig. 2 and at *c* in Fig. 3.

The pivotal supporting-shafts *h* of the switch-cams, from their connection therewith, extend through the cam-cylinder, and each of the outer ends of such shafts is provided with a ring-head, *i*, adjustably fixed thereon by means of a set-screw to engage the pivot-shaft. A spring, *k*, is coiled on the pivot-shaft between its ring-head and the outer face of the cam-cylinder, and one end thereof is connected with the ring-head and its other end with the cam-cylinder in such a manner that when the ring-head is adjusted to regulate the force of *co*

the spring properly and fixed in its adjusted position the action of the springs will tend to hold the switch-cams in contact with the inner face of the cam-cylinder and their inner ends in contact with the under edges of the fixed cams, but in a manner to permit their rounded free ends to rise, as shown in the figures.

A latch, *e*, of sector form, is pivoted in a recess formed in the under edge of the adjustable stitch-cam *D* in such position therein that the free end of the latch will engage the inner upper angle of the adjustable cam *E*, to prevent the needles passing upward over the cam *E* or striking its under angle when the cylinder is moving in the direction indicated in Fig. 2, but will permit the passage of the needles inward over the cam when the cylinder is moving in the direction indicated by the arrow in Fig. 3, in which movement of the needles the latch will rise into the recess in the cam *D*.

In use, with the cam-cylinder in Figs. 1 and 2 moving in the direction indicated by the arrows thereon, if from any cause the needles or any of them are carried to the position shown in the dotted lines, the needle so carried will be struck on its angle-arm *a* by the forward rounded end of the supplementary pivoted cam *d*, as shown in the dotted lines, and, by reason of the relative position of its rounded free end and its pivotal connection with the cylinder, the cam in colliding with the needle will be made to rise from its dotted-line position to its position shown in the solid line, to override the angle-arm of the needle, as shown in the solid lines, to prevent breaking, and cause the needle to pass under the pivoted cam, over the left-hand adjustable cam, *F*, under the stitch-cam *D* and the right-hand adjustable cam, *E*, and in its passage under the heel of the right-hand pivoted cam, *c*, will be made to trace the lower cam, *H*. In this movement of the cam-cylinder, if, after the stitch-cam has passed over the needles, any one or more of them from the rapid movement of the machine or from any other cause should be thrown up, the latch *e* will prevent them colliding with the inner upper angle of the cam *E* and prevent breakage.

In the use of this class of machines in knitting stockings, portions of the work—as those forming the heel and toe of the goods—are produced on but a portion of the needles, and for this purpose the unemployed needles are raised above the action of the cams, and the remaining needles are operated by an alternate back-and-forth or oscillating movement of the cam-cylinder through a portion of a revolution, as indicated by the arrows on Figs. 2 and 3. In the return movement of the cam-cylinder the positions of the parts are shown in Fig. 3, and the operation of the rounded free end of the pivoted cam *e*, in striking a needle, as shown in the dotted lines, will be in every particular the same as described in connection with the pivoted cam *d* in the direct or forward movement of the cam-cylinder.

In the passage of the stitch-cam *D* over the needles in the direction of the arrow in Fig. 3 the pivoted latch *e* will rise within the recess formed within the cam and override the needles.

Inasmuch as the reciprocating movement of the cam-cylinder is usually produced by hand, it is not deemed necessary to employ a pivoted latch on the opposite side of the stitch-cam *D* from the latch shown, because hand-power is under such immediate control that no injury would be likely to result from the rising of a needle; but, if required, such latch may be employed.

The modifications of my improvement represented in Figs. 6 and 8 consist, essentially, of the cam *m*, provided with oblique slots *n* and *n'*, to receive stud-pins *n''*, fixed in the cam-cylinder in such relation to the fixed cams *B* and *C* that the upper edge of the inner end of the cam *m*, when in proper place on the pins, shall engage the under face of the cam *B*, and that force applied to its free outer end will cause it to assume the position represented in the dotted lines. The cams *m* are each held in position on the cylinder by means of a pin, *o*, fixed in the cam and extending through a slot, *o'*, formed in the cylinder and provided with an adjustable ring-head, *o''*. A spring, *o'''*, surrounding the shaft, having one of its ends fixed to the cylinder and its other end fixed to the ring-head, operates to hold the cam in place on the cylinder in the position shown in the solid lines and to permit it to yield to the pressure of the needles on its outer free end and change it to the position shown in the dotted lines to override the angle-arm of the needle and prevent breakage.

In the modification represented in Figs. 7 and 9 the under edges of the fixed cams *B* and *C* are inclined upward, and the upper edges of the inner ends of the cams *p* are beveled to engage the inclined under edges of the fixed cams. These cams *p*, of which one only is shown, of a conformation substantially as shown, are each supported in their position on the inner face of the cylinder by means of a shaft, *p'*, fixed in the cam and extending outward through a slot, *p''*, in the cylinder. A spring, *s*, coiled on the shaft, has one of its ends fixed to the adjustable ring-head *s'* on the shaft and its other end fixed to the cylinder, and operates to hold the cam against the inner face of the cylinder in its forward position, with the beveled edge of its inner end against the under inclined edge of the fixed cam in a manner to permit it to yield and rise to the position shown in the dotted lines when colliding with a needle to override the angle-arm thereof and prevent breakage.

In Figs. 6 and 7 I have omitted the cams *m* and *p* at the left-hand end of the figures to show the slots *o'* and *p''* and the stud-pins *n''* in the cylinders.

I claim as my invention—

1. In a knitting-machine, the combination, with the cam-carrier and the stationary cam,

- of a supplementary switch-cam having a pivotal connection with the carrier, substantially as set forth.
2. In a knitting-machine, the combination, 5 with the cam-carrier and the stationary cam, of a supplementary switch-cam having a pivotal connection with the carrier and a spring to hold the switch-cam in contact with the edge of the fixed cam, substantially as set forth.
- 10 3. In a knitting-machine, the combination, with the cam-carrier and the stationary cam, of a supplementary switch-cam having a pivotal connection with the carrier and a spring to hold the switch-cam in contact with the 15 edge of the fixed cam, the spring connecting the pivotal support of the cam with the carrier, substantially as set forth.
4. The combination, with the cam-carrier and a switch-cam having a pivotal connection 20 with the carrier, of a spring connected to the carrier and to the pivotal support of the cam
- and means for adjusting the spring in its connection with the pivotal support, substantially as set forth.
5. The combination, with the cam-carrier, 25 the stitch-cam, and the adjustable cam, of a latch pivoted at the side of the stitch-cam and adapted to engage the adjustable cam, and thereby prevent the displacement of the needles or engagement with the angle of the adjustable cam, substantially as set forth. 30
6. The combination, with the cam-carrier, the stitch-cam, and with the adjustable cam, of a drop-latch pivoted at the side of the stitch-cam and adapted to rest normally in engagement with the upper portion of the adjustable cam to form a stop and return-guide for displaced needles, substantially as set forth. 35

HOWARD E. HARBAUGH.
